UNITED STATES PATENT OFFICE.

CHARLES G. SARGENT, OF GRANITEVILLE, MASSACHUSETTS.

IMPROVEMENT IN MACHINES FOR WASHING WOOL.

Specification forming part of Letters Patent No. 41,324, dated January 19, 1864.

To all whom it may concern:

Be it known that I, CHARLES G. SARGENT, of Graniteville, in the county of Middlesex and State of Massachusetts, have invented certain new and useful improvements in Wool-Washing Machines; and I do hereby declare the following to be a full, clear, and exact description of the same, reference being had to the accompanying drawings, making a part of this specification, in which—

Figure 1 represents a view of one side of the machine. Fig. 2 represents a view of the opposite side thereof. Fig. 3 represents a longitudinal vertical section through the machine. Fig. 4 represents a broken section through the lifting-wheel. Fig. 5 represents a front view of the rake detached.

Similar letters of reference where they occur in the several drawings, denote like parts of the apparatus in all cases.

Wool-washing machines have been known and used for many years; but there are defects in their operation; as heretofore constructed, which it is my object and purpose to correct.

The lifting-wheels heretofore used for raising the wool up out of the tub or bowl have had their teeth protruded and drawn into an inclosing-cylinder by means of rollers running in cam slots or grooves, which rolls and slots or grooves were immersed in the liquid of the bowl by the rotation of said cylinder or wheel, and which allowed the fiber and dirt to get into said cam-grooves and clog the action of the cylinder. This I have remedied by placing the extending and withdrawing mechanism above or out of the influence of the fiber or of the liquid; and, moreover, by simplifying the construction of said lifting-wheel, have added much to the economy of machine by cheapening its first cost. I have further improved the carrying mechanism between the lifting-wheel and the squeezing-rolls, so as to facilitate the moving of the wool from the lifter to the pressing or squeezing rollers; and I have added fan-wings behind the pressing-rolls for beating up, drying, and carrying the washed wool onto a pile on the floor of the apartment. These additions to the wool-washer have added value and importance to the machine, and have made it a desirable acquisition to manufacturers of wool.

To enable others skilled in the art to make and use my invention, I will proceed to de-

scribe the same with reference to the drawings.

b is a box, tub, or bowl, made of any suitable size and material, and contains the scouring or washing liquid for cleansing the wool, which may be fed into it by an apron, *a*, driven by belts and gearing in any of the ordinary ways. As the wool drops from the apron *a* into the bowl a plunging-cylinder, *c*, catches and immerses in the scouring-liquid. This cylinder *c* may be made with its surface covered with copper, and has three projections, *c'*, upon its periphery for catching and immersing the wool under the liquid, and carrying it forward within the reach of the rake *e*. The rake *e* has a motion given to it near the middle of its handle *h'* by a crank, *f*, which is driven in the direction of the arrow 2. Near the top of the rake there is a swivel-joint, *g*, which allows the rake-handle to pass up and down through it and back and forth through the liquid, to suit the motion of the crank, and to properly guide and steady it. By this arrangement the rake-teeth at their points will pass forward with elliptical motion or sweep through the scouring-liquor, and thus carry the wool forward, and at the same time scour it by moving it through the liquid. If it be desirable to do so, or the length of the machine should require it, two or more of these rakes may be used, all driven and operated substantially like the one shown and described.

The lifting-cylinder *k* receives the washed wool on the points of its protruding teeth, and carries it up in the direction of the arrow 3. The cylinder has an outside shell, *j*, of copper, with perforations through its surface for the teeth to pass through, and has hollow bearings, as shown at *w*. The external cylinder *j*, which has its bearings *x* within the hollow bearings *w*, but of a much smaller diameter, and which is placed inside of the cylinder *k*, works eccentrically to the cylinder *k*. The cylinder *j* has ten (more or less) rows of teeth upon it, which, at certain portions of the revolution of the cylinders, project through the shell *k* and seize the floating wool in certain quantities, and lift it from the liquor and carry it up to the top of the cylinder *k*, at which point the teeth of the cylinder *j* are drawn in, leaving the wool unconfined. As the cylinder *k* continues to revolve the wool is delivered upon the carrying-rolls *l l l*, which have a mo-

tion given to them a little faster than the surface speed of the cylinder *k*, and carry the wool in a uniform and even sheet to the pressing-rolls *m n*, which squeeze out the liquor from the wool, and the liquor thus pressed out falls upon the apron *o* and runs back into the bowl or tub *b*. After the wool passes from between the squeezing-rolls *m n* it is taken by the wings of a fan, *q*, which loosens it up, partially divests it of its moisture, and throws it into a pile upon the floor or other receiver.

Near the bottom of the bowl or tub *b* there is a perforated bottom, *d*, through which the liquor may pass, but not the wool, and below this bottom there should be a draw-off opening, as at *s*, for emptying the bowl or tub of the washing-liquid. The liquor in the bowl or tub may be heated by steam or by steam-pipes in any of the usual well-known ways.

One of the pressing or squeezing rolls, *n*, is weighted, as shown at *p t i*, for the purpose of regulating the pressure upon the wool passing between said rolls.

The drawings represent one way of driving each separate moving part of the machine by means of belts deriving their motion primarily from the crank *y*, which may be turned by hand or by any other first moving-power. Other gearing may be used, if found preferable.

The two cylinders *j k*, though separately described, constitute but one in their opera-

tion, both being necessary to accomplish the object, and might, therefore, be more properly called one cylinder, composed of an interior toothed cylinder and an exterior perforated shell for the teeth of the interior one to protrude through.

Having thus fully described the nature of my improvements upon wool-washing machines, I would state that I am aware that machines resembling mine very much in constructing are in public use, and I lay no claim to the general characteristics of the invention; but

What I do claim, and desire to secure by Letters Patent, is—

1. In combination with the bowl or tub *b*, a lifting-cylinder composed of an inner and outer cylinder, or their equivalents, whose shafts or bearings are eccentric with each other, and arranged to operate substantially as herein represented.

2. The lifting-cylinders *j k*, in combination with the carrying-rolls *l l l*, substantially as and for the purpose described.

3. In combination with the squeezing-rolls *m n*, the fan *q*, for taking, beating up, and throwing the washed wool to its place of deposit, substantially as described.

CHAS. G. SARGENT.
